UNITED STATES PATENT OFFICE

160,479

PAIR OF EYEGLASSES

Louise A. Costa, Baltimore, Md.

Application April 1, 1947, Serial No. 138,082

Term of patent 3½ years

(Cl. D57—1)

To all whom it may concern:

Be it known that I, Louise A. Costa, a citizen of the United States of America, residing at Baltimore, in the State of Maryland, have invented a new, original, and ornamental Design for a Pair of Eyeglasses, of which the following is a specification, reference being had to the accompanying drawing, forming part thereof.

Fig. 1 is a front elevational view of a pair of eyeglasses showing my new design;

Fig. 2 is a top plan view thereof.

Figure 3 is a bottom plan view of a single lens;

Figure 4 is an outer end elevation of the same; and

Figure 5 is a vertical section, as seen on the line 5—5 of Figure 1, looking in the direction of the arrows.

The essential features of my design for a pair

of eyeglasses reside in the specific configuration of the lenses, which are characterized by compound curves, all as illustrated.

I claim:

The ornamental design for a pair of eyeglasses, as shown and described.

LOUISE A. COSTA.
